RICHARD F. DOWNEY, OF MILWAUKEE, WISCONSIN, ASSIGNOR OF SIX-TENTHS TO
ISIDORE M. LEDERER, OF MILWAUKEE, WISCONSIN.

CIGAR-BANDING MACHINE.

1,221,424.

Specification of Letters Patent. Patented Apr. 3, 1917.

Application filed October 6, 1915. Serial No. 54,459.

To all whom it may concern:

Be it known that I, RICHARD F. DOWNEY, a citizen of the United States, and resident of Milwaukee, in the county of Milwaukee and State of Wisconsin, have invented certain new and useful Improvements in Cigar-Banding Machines; and I do hereby declare that the following is a full, clear, and exact description thereof.

- 10 The present invention is directed to the provision of a machine for applying bands to cigars, although the principles involved may be applicable to machines for securing bands or labels to various other articles.
- 18 The primary object of the invention resides in the provision of a machine including a magazine for bands, means for applying paste to and successively removing bands from the magazine and means for bending 25 them about cigars placed in the machine, whereby they may be properly affixed.

An important and more specific object resides in the provision of a single cam-wheel control for all the various mechanisms of 25 the machine, whereby an exceeding simplicity and co-operation of parts is procured.

Another object resides in the provision of a member for taking bands from the magazine which engages suitable stationary 30 paste or other fluid supplying means previously to its engagement with the magazine and wherein the paste applied thereto by such previous engagement serves as a means for catching hold of the bands, and 35 also serves to apply the gum or paste to the bands whereby the ends of the bands may be pasted together during subsequent operations.

Another object resides in the provision of 40 means for clamping the intermediate portion of a band to a cigar and for holding said band and cigar for the operation of certain means for bending the band about the cigar and pressing its pasted end against its unpasted end in position on the cigar.

A further object in connection with the magazine resides in providing such a connection between the magazine and the member which takes a band therefrom that both 50 are simultaneously moved in opposite directions in extracting a band, whereby a ready detachment of the bands from the magazine is provided for.

A still further object resides in the provision in such a machine of a magazine for

supplying bands or labels wherein the bands are fed to the discharge portion of the magazine by spring pressure, and whereby the spring pressure may be relieved at the time of extracting a band from the magazine, so that the band may be very readily withdrawn, by its paste engagement with the carrying member.

With the above and other objects and advantages in view, the invention resides more particularly in the novel combination, arrangement and formation of parts more particularly hereinafter described and particularly pointed out in the appended claims.

Entering now into a brief description of the machine, there is provided a suitably supported main wheel which is driven by any desired means, and which is provided with a cam groove for controlling the actions of the various label clamping and bending mechanisms. A band engaging and carrying finger extends laterally from the wheel and has movement transversely thereon in a limited manner. This finger has wiping engagement with a source of paste supply and is movable to engage a band carried in a pivotally mounted magazine in which the bands are fed toward the mouth by spring pressure, the magazine being resiliently urged into the path of the finger. The magazine carries a stop against which the finger engages and as rotation of the main wheel continues the finger remains stationary against the action of a suitable spring connected thereto and through the medium of an arm carried by the magazine and a stop on the wheel, the magazine is also moved against the action of its spring. During this operation the finger is pressed against the uppermost band and the spring pressure is relieved in the magazine by a cam carried on the wheel engaging arm thereof, this arm having slight independent movement to actuate the cam. The finger is released from the stop of the magazine at the time the magazine is released from the stop of the wheel, and thus both jerk simultaneously in opposite directions and the outermost band of the magazine adheres to and is carried with the said band carrying arm. This arm then moves around on the wheel to dispose the band over a cigar placed in a suitable support. By the action of a roller in the cam groove of the wheel, a clamping member presses the cigar and band

on the support, the band-carrying arm standing still during this movement. Bending fingers then move downwardly and bend the band at the sides of the cigar, an end 5 securing finger actuated by a second roller in the groove then bends the unpasted end of the band inwardly under the cigar and holds it and a wiper finger moves laterally and bends the pasted end of the band around 10 the cigar, whereby the band is properly secured on the cigar. The clamping shoe then moves upwardly from the cigar and the end-holding finger is retracted from between the ends of the band so that the cigar 15 with the band pasted thereon may be withdrawn from the machine. The machine is thus entirely automatic in its action, the only manual operation being feeding and removing the cigars.

20 Reference is had to the accompanying drawings wherein similar characters of reference designate corresponding parts throughout the several views and in which:

25 Figure 1 is a front elevation of the improved band-applying machine, showing the relation of parts assumed immediately prior to extracting a band from the band magazine;

30 Fig. 2 is a central vertical sectional view through the machine on the line 2—2 of Fig. 1;

35 Fig. 3 is a horizontal sectional view taken through the machine on the line 3—3 of Fig. 1 and showing the means for actuating the wiping and band end holding fingers of the machine;

40 Fig. 4 is a detailed sectional view on the line 4—4 of Fig. 1 showing the means for retracting the band end holding finger after the wiping finger has secured the pasted end of the band;

45 Fig. 5 is a transverse sectional view taken through the magazine on the line 5—5 of Fig. 1;

50 Figs. 6, 7, 8, 9, 10 and 11 show the various steps in the operation of clamping the cigar and band and of bending the band about the cigar and pasting it; Fig. 6 shows the initial position with the band drawn over the cigar; Fig. 7 shows the clamping shoe moved downwardly to clamping position; Fig. 8 shows the side bending fingers moved downwardly to bend the band around the upper side of the cigar; Fig. 9 shows the unpasted end-holding finger moved laterally to hold the unpasted end of the cigar in position; Fig. 10 shows the wiper finger moved laterally to secure the pasted end of the band, and Fig. 11 shows the final step 60 wherein the wiper finger is moved past the band, the bending fingers are moved apart and the clamping shoe is raised to permit the removal of the cigar and permit the insertion of another.

65 Fig. 12 is a fragmentary front elevation

of the mechanisms for bending and securing the end portions of the cigar bands, and showing said mechanisms in their initial positions.

Referring now more particularly to the accompanying drawings, the preferred embodiment of the machine is shown as comprising a main standard 10 which is mounted on a base 11 and which is intermediately provided with a sleeve 12 in which is threaded one reduced end 13 of a journal shaft 14. The other and forward end of the shaft is also reduced at 15 and carries an immovable sleeve 16 which is provided with ears 17 at its ends, to which are secured inner and outer vertical plates 18 and 19 having angularly bent upper portions 20 forming seats for the intermediate portion of a cigar and its inner end. Mechanisms for bending and securing the end portions of the band under the cigar are carried by the plate 19 and mechanisms for clamping the cigar on the seats 20 and for bending a band downwardly at the sides of a cigar are carried by a forward extension 21 of the standard. The forward plate 19 carried by the shaft is extended downwardly to the base at 22 and reinforced to assist in holding the sleeve 16 from turning and to support the forward end of the shaft.

Journalized on the shaft 14 is the main wheel 23 of the machine, which includes the hub 24 and the rim portion 25 grooved to receive a drive belt 26, although it is appreciated that the wheel might, if desired, be 100 as readily driven by a suitable gear connection. Journalized on the outer portion of the hub of the wheel is an arm 27 held adjacent the web of the wheel by a sleeve 28 extending between it and the plate 18. The intermediate portion of the arm is transversely enlarged to provide for an arcuate slot 29 in which is slidable a bolt 30 engaged in the web of the wheel, whereby the arm is permitted a limited transverse sliding movement 110 on the wheel. The outer end of the arm is bent forwardly from the wheel at 31 to provide the band-carrying finger, the outer end of the finger being provided with a cupped enlargement 32.

115 This band-carrying finger is adapted to extract a band from the magazine, hereinafter to be described in detail, by reason of paste on said finger taken from the paste-supply means also to be described later and to carry said band over the cigar-seating support portions 20 so that the band may be properly applied.

120 Looking now at the front of the machine it is seen that the main wheel rotates in a clockwise direction and that the band-carrying arm and finger are urged to rotate in a clockwise direction within the limit of their relative movement with respect to the wheel by a spring 33 secured at 34 to the inner end 125

130 of the bolt 30 and to the inner end of the sleeve 28. The spring 33 is wound around the bolt 30 and is held in position by a lock washer 35.

of the arm and at 35 to the web of the wheel. The purpose of this limited movement of the band-carrying arm is to permit it to remain idle during rotation of the wheel while the clamping shoe is moving into operation, and also while it is engaging the band magazine.

Taking up now the specific mechanism for clamping the cigar and band together on the seat, and the means for bending the band at the sides of the cigar, while it is clamped, it is seen that the forwardly directed upper end 21 of the main standard is bifurcated to provide spaced bearings 36 for a pair of vertical shafts 37 having their lower ends connected by a bar 38, from the central portion of the inner side of which depends a lug 39 carrying an inwardly extended pindle 40 on which is journaled a roller 41, which rides in a cam groove 42 formed continuously in the web of the main wheel 23 adjacent its periphery. A portion 42^a of this groove is inwardly offset and concentrically curved with respect to the main portion, designated at 42^b, and is connected to the major portion of the groove which comprises substantially half the circumference by straight portions 42^c. Carried at the extremities of the furcations of the standard portion 21 and depending therebelow is a guide-plate 43, in bearings 44 on the rear face of which is slidably held a bar 45 having its lower end forwardly directed to lie between the seat portions 20 for the cigar to form a clamping shoe 46. Mounted for vertical sliding movement on the front face of the plate 43 is a block 47 which has pivoted thereto the upper ends of a pair of depending arms 48 carrying at their lower ends outstanding portions 49 which form the side bending fingers. The upper portions of the bars 48 are connected by a pair of pivoted links 50 and a retractile spring 51 connects the intermediate portions of these bars. Pivoted at the pivotal connection of the links is a bar 52 which extends upwardly and is attached to a lug 53 depending from a transverse bar 54 secured to and connecting the upper ends of the shafts 37. The upper portion of the bar 52 is provided with a longitudinal slot 55 and a pin 56 is carried by the upper end of the clamping shoe bar 45 and is slidable in this slot. The said clamping shoe bar is resiliently urged to downward position by a retractile spring 57 connected with its upper end and with the lower furcation of the standard portion 21. To permit movement of the bending fingers 49 past the sides of the clamping shoe, guide portions 46' extend diagonally upward and inward from its sides.

As the cam roller 41 enters one of the cam groove portions 42, the entire structure of the clamping and band side-bending mechanism moves downwardly to a position where-

in the clamping shoe presses on the band and cigar and clamps it on the seat. As movement in the portion 42^b continues the bar 52 drawn by the shafts 37 moves downwardly, with respect to the links 50 and moves the bars 48 and the band side bending fingers downwardly to the sides of the cigar, it being noted that a firm but at the same time yielding movement for these side-bending fingers is had by reason of the sliding plate 47. As the roller enters the portion 42^a of the groove, this mechanism remains motionless, holding the cigar clamped upon the seat and the band bent down at the sides thereof, while the ends are bent in and pasted. Upon the roller entering the other grooved portion 42^b the parts of the mechanism are retracted to their original position.

As the band-carrying finger moves into 85 the position for placing the band over the cigar, it is momentarily held against movement to permit the clamping shoe to move to operative position by means of an angular stop 57 pivoted on a depending projection 58 of the plate 43 and having a retractile spring 59 secured to one arm and to the plate to urge its other arm into the path of movement of the finger. This spring 59 is stronger than the spring of the band-carrying finger and when the finger engages the arm of the angular member, it will be held against movement during the period of its permitted relative movement with respect to the wheel. Upon its reaching this limit due 100 to engagement of the pin 30 at the end of the slot 29, it will rock the angular member 57 and move with the wheel. During this time the clamping shoe will have clamped the band and the finger will thus move free 105 therefrom.

The mechanism for bending the ends of the band inwardly and securing the pasted ends includes a bar 60 which is held for transverse sliding movement across the inner 110 face of the plate 18 above the shaft 14 by means of pins 61 carried by the plate and slidably in slots 62 of the bar. The right hand end of this bar, looking from the front, is directed inwardly at 63 and carries a 115 pindle on which is mounted a cam-roller 63* also riding in the cam groove heretofore described. Secured transversely across the front face of the plate 18 and spaced outwardly therefrom is a track-bar 64, on which 120 is slidably mounted a sleeve 65 carrying a pair of transversely spaced ears 66, the outermost of which is offset forwardly from the sleeve. Slidably and rotatably mounted in the ears is a shaft 67, which extends rearwardly of the plate through a transverse slot 68 therein and which has its rear end upwardly offset at 69 to form the holding finger for bending and securing the unpasted end of the band. This finger is yieldably 130

held in a raised position by a spring 70 secured to the sleeve and to an arm 71 projecting laterally from the forward end of the shaft 67. The finger 69 is movable to and from a position adapted to engage the unpasted end of the band, and is normally urged to such position by a spring 72 on the shaft 67 between the ears and bearing against the outermost ear and a stop 73 on the shaft. The means for moving this finger to the right from a position at the left of the machine, to bend the unpasted end of the band under a cigar and hold it there during operation of means for bending the pasted end of the band includes a lever 74 which extends upwardly from a pivotal connection at 75 with the plate 18 and which has its upper end bifurcated to slidably embrace a pin 76 projecting outwardly from the sleeve. A lever 77 is intermediately pivoted at 78 to the plate 18 adjacent the left-hand end of the bar 60 and is engageable by a stop 79 carried by the bar upon movement of the bar toward the left, whereby said lever is rocked. The lower end of this lever is connected to the intermediate portion of the lever 74 by a link 80 and thus such rocking movement will move the sleeve 65 and consequently the band end holding finger 69 to bend the end of the band under a cigar. The initial relation of parts for such movement is indicated in Fig. 12. Upon the finger being moved to this position, the lever 77 rides under the stop 79.

For bending the pasted end of the band under the cigar, and pressing it against the unpasted end to effect a proper securing of the band, a wiper finger 81 is provided, which extends upwardly from a pivotal connection with ears 82 provided on the sleeve 16 and which, has a flexible end portion formed in this instance of a rubber strip 83. This wiper finger is resiliently urged to a position wherein it extends at an angle toward the right side of the machine by a leaf spring 84 secured to the sleeve 16 and slidably bearing against the said finger. The bar 60 carries an inwardly extending finger 85 adapted to slidably engage the wiper finger and upon the end-holding finger 69 reaching its holding position, continued movement of the bar due to further movement of its roller 63 in the groove portion 42^b will continue to swing the wiper finger to the left to thus bend the pasted end of the band inwardly and firmly press it against the other end.

The operation of applying the band is then completed with the exception that the end-holding finger 69 lies between the ends of the band, and to retract it to permit the banded cigar to be readily removed, a bar 86 is passed transversely through the plates 18 and 19 and held thereby for sliding movement, being normally urged inwardly toward

the main wheel 23 by a retractile spring 87. This bar carries, adjacent the plate 19, a laterally extending finger 88, which upon outward movement of the bar is engageable against the shaft 67 at its offset to form the finger 69, when said shaft is in a position for holding a band end. This outward movement of the bar is effected by a cam block 89 carried on the forward face of the wheel 23.

When the cam-roller 63^a enters the second portion 42^b of the cam groove, the parts are moved back to initial position by moving the bar 60 to the right. In this connection it is noted that the stop 79 comprises a member pivoted to the bar 60 in such manner as to permit clockwise movement to facilitate its movement past the upper end of the lever 77. The end of the bar 60 carries a stop 90 which engages the lever 77 and swings it to move the sleeve and consequently the holding finger 69 to the left, the wiping finger being moved to the right by action of the spring 84 as the pin 85 moves to release it.

Figs. 6 to 11 inclusive illustrate the cycle of operations heretofore described with respect to the cigar and band. The clamping shoe 46, the side bending fingers 49, the unpasted-end holding finger 69 and the wiping finger 81 engage the band successively in the order named to properly secure the band, and upon the band being secured these parts with the exception of the wiping finger which moves away therefrom during its operation, are withdrawn from the band in a simultaneous manner, the cam block 89 being so arranged on the face of the wheel as to effect such simultaneous action with respect to the holding finger 69.

The means for supplying paste to the cup portion 32 of the band-carrying finger includes a receptacle 91 secured at the right-hand side of the plate 19 and lying inwardly of said plate and outwardly of the path of movement of the band-carrying finger 31. Transversely journaled at the outer portion of the receptacle is a shaft 92 which extends past the ends of the receptacle and carries at one end an arm 93 extending inwardly into the path of the said band-carrying fingers. The other end of the shaft carries a depending arm 94 to which and to the side of the receptacle is secured a retractile spring 95, movement of the shaft due to this spring being limited by a stop 96 on the receptacle engaging said arm 94. The intermediate portion of the shaft carries an inwardly extending plate 97 which has its inner end bent downwardly in a slightly arcuate manner as at 98. This plate is normally held by the spring 95 into raised position to hold its bent portion 98 slightly in the path of the band-carrying finger 31, so that as the finger moves past it will have a wiping engagement with said portion 98 to obtain a

- proper amount of paste, placed at its cup portion 32. As the arm moves downwardly past this portion 98 it trips the arm 93 which rocks the shaft and thus immerses the downwardly turned portion 98 of the plate 97 in the paste so that a fresh supply of paste is had on said portion. The plate 97 and portion 98 are preferably formed of somewhat resilient material.
10. Taking up now the specific magazine structure, there is provided a casing including the side walls 99, the outer end wall 100 and the bottom wall 101, the side walls being extended past the bottom wall and pivotally mounted on a standard 102 upstanding from the base 11 to permit pivotal movement of the entire magazine whereby its upper end moves in a path parallel to intersecting the path of movement of the band-carrying finger. The upper outward corner of the magazine is resiliently urged into the path of movement of the said band-carrying finger by a retractile spring 103 secured to the extended side wall portions and to the depending portion 22 of the front plate. Slidably passed through the bottom wall 101 of the magazine chamber is a follower shaft 104 which carries within the chamber a follower plate 105 which is resiliently urged toward the opposite discharge portion of the chamber by a spring 106 surrounding the shaft. Retaining fingers 107 extend inwardly from the sides of the top of the chamber to hold a plurality of bands in the chamber. The chamber is provided with an inner end wall 108 which is slidably adjustable to permit the insertion of a fresh supply of bands in the magazine by means of inwardly turned flange portions 109 disposed between edge portions of the side wall plates 99 and receiving clamping screws 110 which are passed through slots 111 in said edge portions. The magazine is normally held at such an inclination with respect to the path of movement of the carrying arm by means of a stop pin 112 carried on an upward extension 113 of the standard 102 that the carrying arm is adapted to engage its upper outer corner, and to hold the arm in such engagement a stop 114 projects from this corner. Journally mounted in the downwardly extended portions of the side walls 99 is a shaft 115 which carries at its inner end an upturned arm 116 which is adapted to be engaged by a stop-pin 117 carried on the back of the main wheel 23. Carried intermediately on the shaft 115 is a cam-collar 118 which, upon rotation of the shaft due to engagement of the arm 116 by the stop 117, engages the follower plate shaft 104 and slightly retracts and binds it to thus relieve the pressure on the bands in the magazine chamber whereby a band may be very readily withdrawn from under the holding fingers 107. This shaft 115 is limited in its pivot 1 movement by engagement of stops 119 with the cam portion of the cam collar, and the shaft is normally urged to a position wherein the cam is inoperative by a retractile spring 122 secured to one of the extended side wall portions and to a depending arm 121 on the said cam collar.
- It is seen that only a slight movement of the arm 116 serves to actuate the cam to relieve the spring pressure in the magazine. Further movement of the wheel causes the arm 116 to swing the entire magazine outwardly with respect to the path of the carrying finger 31. The stop 117 and arm 116 and the carrying arm and its stop 114 are so relatively positioned that both stops release simultaneously. Thus the finger and magazine jerk in opposite directions to the action of their respective springs. It is noted that the arcs of movement of the carrying finger and of the adjacent corner of the magazine intersect and thus as the finger and magazine move, the finger is pressed against the band to facilitate proper application of the paste on the finger to the band. It is seen that the finger is in engagement with the band end without relative movement for a considerable time and thus in combination with the pressure just mentioned a proper sticking engagement of the paste is assured so that the band will adhere to and be carried by the said carrying finger.
- The operation of the magazine with respect to the rest of the mechanism is such that the carrying finger is procuring a band therefrom at the time that the folding and bending operations of the machine are being completed.
- The machine is thus entirely automatic in its operation with the exception of placing cigars therein and removing them. Various machines have heretofore been devised wherein the cigars are automatically fed, but in actual practice it is necessary that the cigars be fed manually as the shape of the cigar determines the relative position of the face of the band, and no automatic feed has been devised to properly feed cigars to effect this result.
- It is noted that the band-carrying finger carries the band over the cigar in the machine so that the central face portion of the band is positioned at the top side of the cigar in the machine. This is an important labor-saving feature, as the operator must determine the best side of the cigar on which to apply the band face, and thus the best side of the cigar may be determined by looking down on the cigar in its movement into the machine, without necessitating any subsequent moving or turning of the cigar after the proper side has been determined.
- I claim:
1. A label applying machine including an article support, label bending means associ-

ated with the article support, a main wheel connected with the label bending means for operation thereof, a label magazine and a label carrying arm carried by the wheel for extracting a label from the magazine and carrying it adjacent the article support.

5. A label applying machine including an article support, means for clamping a label to the support, a main wheel connected with the clamping means for operation thereof, a label magazine and a label carrying arm carried by the wheel for extracting a label from the magazine, and carrying it adjacent the article support.

15. A label applying machine comprising a main wheel, an article support, a clamping and side bending mechanism connected with the wheel for operation thereby, an end bending mechanism having engagement with the wheel for operation thereby, a label magazine and a label carrying member carried by the wheel for extracting a label from the magazine and carrying it adjacent the article support.

25. A label applying machine including an article support, means for moving a label adjacent to said support, and means operative successively for holding a label to the article, for bending the label about the sides 30 of the article, for bending and holding one end of the label inwardly, for bending the other end of the label inwardly to engage the first end and for retracting the means for bending the first named end of the label 35 in a direction laterally with respect to its path of engaging movement.

5. A label applying machine including an article support, a label magazine, a fluid supply means including a stationary container, and a label carrying member movable successively to engage said fluid supply means, to engage and extract a label from the magazine and to carry said label adjacent the article support.

40. A label applying machine including an article support, a cam wheel, a magazine, a carrying arm carried on said wheel, means for bending a label around an article carried on the support operable by the cam of said 45 wheel and said carrying arm being engageable with the magazine to extract a label therefrom and carry it adjacent the article support.

7. A label applying machine comprising 55 an article support, means for clamping an article to the support, a label magazine, a continuously rotatable member and a label carrying means carried by said member and engageable with the magazine to extract a 60 label therefrom and movable between the clamping means and the support transversely of the path of movement of said clamping means.

8. A label applying machine comprising 65 an article support, means for clamping an

article to the support, a continuously rotatable member having operative connection with the article clamping means, a label magazine, a label carrying member carried by the rotatable member and engageable with the magazine to extract a label therefrom, and means for momentarily arresting movement of the label carrying member adjacent the support.

9. A label applying machine comprising 75 an article support, means for clamping an article to the support, a label magazine, a continuously rotatable member, a label carrying member carried by the rotatable member and engageable with the magazine to extract a label therefrom and convey it adjacent the support, said label carrying member having limited movement with respect to the rotatable member and being resiliently urged in one limit of such movement and a 80 spring-held detent member engageable with the label carrying member adjacent the article support.

10. In a label applying machine, an article support, means for bending a label initially 90 about the sides of an article on the support, a finger movable transversely of the support to engage one end of a label and a finger oppositely movable to engage the other end of a label.

11. In a label applying machine, an article support, means for bending a label initially 95 about an article on the support, a finger movable transversely of the support to engage one end of a label, a finger oppositely movable to engage the other end of a label, and means for moving one of the fingers laterally of its direction of movement to engage a label.

12. In a label applying machine, an article support, means for bending a label initially 105 about the sides of an article on the support, a bar movable transversely of the support and label end engaging fingers connected with the bar and oppositely movable upon movement thereof.

13. In a label applying machine, a body, an article support, means for bending a label initially about an article on the support, a bar movable transversely of the support, a 115 label end holding finger movably secured to the body, a label end wiper finger connected with the bar, a lever pivoted to the body and connected with the said holding finger, a second lever intermediately pivoted to the 120 body and connected at one end with the first lever and a connection between the other end of the second lever and the bar.

14. In a label applying machine, a body, an article support, means for bending a label initially about an article on the support, a bar movable transversely of the support, a label end holding finger movably secured to the body, a label end wiper finger connected with the bar, a lever pivoted to the 125 130

- body and connected with the said holding finger, a second lever intermediately pivoted to the body and connected at one end with the first lever and a connection between the other end of the second lever and the bar, releasable in the last portion of movement of the bar in one direction.
15. In a label applying machine, an article support, means for bending a label initially about an article on the support, a finger movable transversely of the support to engage one end of a label, a finger oppositely movable to engage the other end of a label, and means for arresting movement of one of the fingers during the last portion of the operative movement of the other finger.
16. In a label applying machine, an article support, means for bending a label initially about an article on the support, a finger movable transversely of the support to engage one end of a label, a finger oppositely movable to engage the other end of a label, means for arresting movement of one of the fingers during the last portion of the operative movement of the other finger, and means for moving said finger laterally of its direction of movement to engage a label upon completion of operative movement of said other finger.
17. In a label applying machine, an article support, means for bending a label initially about an article on the support, a wheel having a cam portion, a bar connected with said cam portion and movable thereby transversely of the support, label end engaging fingers connected with the bar and transversely movable upon movement thereof, one of said fingers being movable transversely of its movement to engage a band, and a second cam on the wheel engageable with said finger to effect such movement.
18. In a label applying machine, an article support, means for bending a label initially about an article on the support, a carriage slideable transversely of the support, a label end holding finger including an offset portion journaled on the carriage, means resiliently holding the finger against rotation, and a label end wiper finger movable oppositely with respect to the holding finger.
19. In a label applying machine, an article support, means for bending a label initially about an article on the support, a carriage slideable transversely of the support, a label end holding finger including an offset portion transversely slidably journaled in the carriage, means resiliently holding the finger against rotation, a label end wiper finger movable oppositely with respect to the holding finger, and means for moving the holding finger transversely of the carriage.
20. In a label applying machine the combination of an article support, a carriage movable toward and away from the article support, a clamping shoe resiliently urged toward the article support and having limited movement with respect to the carriage and a pair of spring connected side bending fingers carried by the carriage at the sides of the shoe.
21. In a label applying machine the combination of an article support, a carriage movable toward and away from the article support, a clamping shoe resiliently urged toward the article support and having limited movement with respect to the carriage, a pair of spring connected side bending fingers carried by the carriage at the sides of the shoe, and inwardly inclined guide portions for the side bending fingers carried by the shoe.
22. In a label applying machine the combination of an article support, a carriage movable toward and away from the article support, a clamping shoe resiliently urged toward the article support and having limited movement with respect to the carriage, a pair of spring connected side bending fingers, slidably pivoted to the carriage at the sides of the shoe, a pair of pivotally connected links connecting the fingers and a link connecting said pair of links and the carriage.
23. In a label applying machine, an article support, a carriage movable toward and away from the support, a pair of spring connected side bending fingers slidably connected with the carriage, a pair of pivotally connected links connecting the fingers, and a link connecting said pair of links and the carriage.
24. In a label applying machine, an article support, a carriage movable toward and away from the support, a block slidably carried by the carriage, a pair of spring connected side bending fingers pivoted to the block, a pair of pivotally connected links connecting the fingers, and a link connecting said pair of links and the carriage.
25. A label applying machine including an article support, a movable label magazine, a carrying member movable toward and away from the magazine and adapted to detach a label therefrom, and means for moving the magazine simultaneously with movement of the carrying member.
26. A label applying machine including an article support, a movable label magazine, a carrying member movable toward and away from the support and the magazine, means for supplying paste to the carrying member, and means for moving the magazine simultaneously with movement of the carrying member thereabout and in a path intersecting the path of the carrying member.
27. A label applying machine including a magazine, a continuously moving member, a label carrying finger carried by the moving member and having relative movement and normally urged to one limit of such movement.

- movement, said label carrying finger being engageable with the magazine to successively extract labels therefrom, and said label carrying finger being arrested in its movement during a portion of the movement of the continuously moving member by engagement with the magazine.
28. A label applying machine including a swingingly mounted magazine normally urged to one limit of swinging movement, a movable carrying member, an arm on the carrying member adapted for trip engagement with the magazine to swing it and means carried by the arm for successively engaging labels in the magazine.
29. A label applying machine including a swingingly mounted magazine normally urged to one limit of swinging movement, a movable carrying member, an arm on the carrying member adapted for trip engagement with the magazine to swing it, means carried by the arm for successively engaging labels in the magazine, and said arm having relative movement with respect to the carrying member whereby its motion is arrested upon initial engagement with the magazine.
30. In a label applying machine, a label magazine including a label compartment, a spring urged follower in the compartment, a label carrying member movable toward and away from the magazine to successively engage labels therein, and means associated with the label carrying member for relieving the spring pressure of the follower upon movement of said label carrying member thereadjacent.
31. In a label applying machine, a label magazine including a label compartment, a follower in the compartment, a spring urged stem for the follower, a shaft disposed transversely of the stem, a member on the shaft engageable with the stem to retract it upon rotation of the shaft, a label carrying member movable toward and away from the magazine to successively engage labels therein and means for rotating the shaft upon movement of said label carrying member.
32. In a label applying machine a label magazine including a label compartment, a
- follower in the compartment, a spring urged stem for the follower, a shaft disposed transversely of the stem, a cam on the shaft engageable with the stem to retract it upon rotation of the shaft, a label carrying member movable toward and away from the magazine to successively engage labels therein and means for rotating the shaft upon movement of said label carrying member.
33. In a label applying machine, a rotatable member, a label magazine thereadjacent including a label compartment, a follower in the compartment, a spring urged stem for the follower, a shaft disposed transversely of the stem, a member on the shaft engageable with the stem to retract it upon rotation of the shaft, an arm projecting from the shaft into the path of movement of a portion of said rotatable member, and means carried by the rotatable member for successively engaging labels in the magazine.
34. In a label applying machine, a stationary fluid container, a fluid supply member movable thereinto, a movable label engaging member movable toward and away from the fluid supply member for engagement therewith, and means for moving said fluid supply member into the container upon successive engaging movements of the label engaging member.
35. In a label applying machine, a stationary fluid container, a pivoted fluid supply member movable to engage a portion thereof in the container and normally urged to hold said portion out of the container, a rotatable member, a label engaging member carried thereby and engageable with said portion of the paste supply member and an arm extending from the paste supply member for trip engagement with a portion of the rotatable member.
- In testimony that I claim the foregoing I have hereunto set my hand at Milwaukee, in the county of Milwaukee and State of Wisconsin, in the presence of two witnesses.
- RICHARD F. DOWNEY.

Witnesses:

GEO. W. YOUNG,
M. E. DOWNEY.
